TUMBLING MACHINE

James P. Di Gregorio, 239 Admiral St., Providence, R.I.
Filed Sept. 10, 1963, Ser. No. 307,827
1 Claim. (Cl. 134—104)

The present invention relates to improvements in tumbling machines.

An object of the present invention is to provide an improved tumbling machine wherein the articles to be tumbled are sealingly confined in the tumbling tank with the tumbling liquid.

Another object of the present invention is to provide an improved tumbling machine wherein the tumbling tanks are imperforate and contain the articles to be tumbled with the liquid and separator means are associated with the tumbling tanks to separate the articles from the liquid upon completion of the tumbling operation.

A further object of the present invention is to provide an improved tumbling machine wherein multiple tumbling tanks can be conjointly operated with a common drive means.

A still further object of the present invention is to provide an improved tumbling machine wherein the tumbling liquid is contained in the tumbling tank with the articles to be tumbled and separated from the articles after tumbling, there being means provided for returning the liquid to the tanks for re-use.

Other objects of the present invention are to provide an improved tumbling machine which conserves space, provides ease in handling, lowers labor costs and is cleaner to utilize.

Various other objects and advantages will become apparent from the detailed description to follow.

In the drawings:

FIGURE 1 is a side elevational view of the tumbling machine;

FIGURE 2 is a top plan view thereof;

FIGURE 3 is a front elevational view thereof;

FIGURE 4 is a detail view of one of the tumbling tanks; and

FIGURE 5 is a side elevational view of the tumbling tank of FIGURE 4, with part being broken away.

Referring more particularly to the drawings, wherein like numerals refer to like parts throughout, it will be seen that I have provided an improved tumbling machine 10 which includes a framework 12, tumbling tanks or barrels 14, drive means 16, separator means 18, liquid reservoir means 20 and pump means 22.

The framework 12 is of simple construction including four vertical corner angle irons 24 joined at the top and at the bottom by the front bars 26, rear bars 28 and side bars 30. For support of the drive means 16, cross bars are provided at 32, 34 and 36, 38. Motor supports 40 are carried by the side bars 30 and cross bars 32 and 38.

Also, for the support of the tumbling tanks 14, the bars 42 join the vertical corner angle irons 24 at the sides. As seen in FIGURE 3 additional vertical supports are provided at 44 at the front and rear of the framework. The bars 46 extend front to rear connecting the vertical supports 44 for support of the tanks 14 as will be described. Additional bars 48 extend front to rear for the support of the separator means 18.

Having reference now to FIGURES 4 and 5, the structure of the tanks 14 will be described. Each tank is preferably constructed of wood to octagonal shape with closed ends 50 and an opening 52 in one of the faces thereof. Each end 50 has a flanged bearing stud 54, 56

2

secured thereto, as by screws 58. The studs are journalled in the bearings 60 carried by the bars 46 and 48.

The closures 62 for the openings 52 are constructed of wood at 64 beveled to cooperate with the beveled opening. A rubber or rubber-like gasket 66 overlies the wood 64 to cooperate with the mouth of the opening 52. A metal backing plate 68 is joined to the wood 64 by bolts to clamp the gasket therebetween and to sealingly hold the gasket against the tank when clamped as will presently be described.

At each end of each tank a cam lock plate 70 is secured with a portion outstanding at 72 in line with and over the closure 62. A rod 74 is provided with a handle 76 and cam locks 78 adapted to bear against the plate 68. The rod 74 has its ends engaged in the slots 80, see FIGURE 1, so that when the handle 76 is rotated the cam locks 78 bear against the plate 68 to sealingly clamp the closure 62 over the opening in the tank. When it is desired to open a tank, the handle is reversely rotated and the whole handle and rod assembly is removed by disengagement from the slots 80 and then the closure can be removed.

The drive means 16 includes two electric motors 82, one for each pair of tanks. Each motor has a chain drive including chains 84, 86, 88 over sprockets 90, 92, 94, 96; 25 and 98, 100, so as to drive a pair of tanks.

The separator means 18 includes a trough 102 for each tank, slidably supported on the angle iron bars 48, as is seen in FIGURE 3. Each trough is preferably formed of sheet metal to a desired shape and has a pair of angle iron tracks therein at 104 to support a removable wire mesh screen 106 beneath each tank.

The top trough communicates with the lower trough through pipe 108 and the lower trough communicates through strainer 110 and pipe 112 to reservoir 20. The latter has an access cover at 114 through which additional liquid can be added. A pump 22 is connected to the reservoir 20 and has an outlet hose 116 whereby the liquid can be recirculated to any of the tumbling tanks.

In operation, the articles to be tumbled, such as jewelry, are placed in a tank and a suitable supply of liquid is added, such as soapy water. Any other liquids susceptible of use may be utilized, as will be understood. After rotatably driving the tank for a period of time, the motor is stopped, the cover removed as above described and the contents drop down onto the screen and the liquid passes into the trough and down to the reservoir for re-use. The screen with the tumbled articles then can be removed.

In view of the foregoing, it is believed that I have provided an improved tumbling machine which fulfills the objects hereinbefore enumerated.

As this invention may be embodied in several forms without departing from the spirit or essential characteristics thereof, the present embodiment is therefore illustrative and not restrictive, since the scope of the invention is defined by the appended claim rather than by the description preceding it, and all changes that fall within the metes and bounds of the claim or that form its functional as well as conjointly cooperative equivalents, are therefore intended to be embraced by this claim.

60 I claim:

A tumbling machine comprising a framework, at least a pair of water tight tanks rotatably journalled on said framework, each of said tanks having an opening through which the items to be tumbled and the tumbling liquid can be introduced and removed, a closure for the opening in each of said tanks, means sealingly, releasably clamping each said closure to its respective tank, drive means connected to one of said tanks for effecting rotation thereof, coupling means drivingly interconnecting the second of

said pair of tanks with said one tank, a liquid collecting trough carried by said framework below each of said tanks to collect liquid from the tanks after completion of the tumbling operation, and a separator screen removably mounted in each of said troughs for isolating the items from the liquid after tumbling, and a central supply reservoir for the liquid having communication with said troughs to receive the liquid therefrom, and pump means on said reservoir for redistributing the liquid to any of said tanks.
